US00D768291S

(12) **United States Design Patent** (10) Patent No.: **US D768,291 S**
Carota et al. (45) Date of Patent: ** Oct. 4, 2016

(54) **APPLICATOR FOR LIQUID PHARMACEUTICAL COMPOSITIONS**

(75) Inventors: **Mark Carota**, Chemsford, MA (US);
Tom Boyajian, Wilmington, MA (US);
Teresa Nelson, Kingston, NH (US)

(73) Assignee: **DUSA PHARMACEUTICALS, INC.**,
Wilmington, MA (US)

(**) Term: **14 Years**

(21) Appl. No.: **29/413,178**

(22) Filed: **Feb. 13, 2012**

(51) LOC (10) Cl. **24-02**

(52) U.S. Cl.

USPC **D24/119**
